ELECTRICIAN'S INSULATION STRIPPING PLIERS

Hans Wiener, Taby, Sweden, assignor to
Pressmaster Ltd., Stockholm, Sweden

Filed Aug. 2, 1974, Ser. No. 494,274

Claims priority, application Switzerland Feb. 4, 1974

Term of patent 14 years

Int. Cl. D8—05

U.S. Cl. D8—52

FIG. 1

FIG. 2

FIG. 3

FIG. 1 is a top plan view of the electrician's insulation stripping pliers showing my new design;

FIG. 2 is a side view thereof, the opposite side being a mirror image;

FIG. 3 is a front view thereof;

FIG. 4 is a rear view thereof;

FIG. 5 is a bottom plan view thereof; and

FIG. 6 is a side view of a second embodiment of the electrician's insulation stripping pliers.

I claim:

The ornamental design for an electrician's insulation stripping pliers, as shown and described.
